(57) **CLAIM**

The ornamental design for a bluetooth enabled alarm clock, as shown and described.

DESCRIPTION

FIG. 1 is a front, perspective view of a bluetooth enabled alarm clock showing my new design;

FIG. 2 is a front view thereof;

FIG. 3 is a rear view thereof;

FIG. 4 is a top view thereof;

FIG. 5 is a bottom view thereof; and,

FIG. 6 is a right side view thereof, the opposite side view being a mirror image.

The equal length broken lines in drawing FIGS. 1, 2, 4, 5 and 6 illustrate a mesh. The unequal length broken lines in the drawings illustrate surface shading.

1 Claim, 6 Drawing Sheets
